Inventor
Guy G. Martin
by Orring & Hague Atty's

UNITED STATES PATENT OFFICE.

GUY G. MARTIN, OF MASON CITY, IOWA.

VANITY CASE.

Application filed November 7, 1922. Serial No. 599,503.

To all whom it may concern:

Be it known that I, GUY G. MARTIN, a citizen of the United States, and a resident of Mason City, in the county of Cerro Gordo, State of Iowa, have invented a certain new and useful Vanity Case, of which the following is a specification.

The object of my invention is to provide a vanity case of simple, durable and inexpensive construction of small size designed to contain a readily accessible mirror and toilet articles such for instance as powder, rouge and cosmetic sticks, etc.

More specifically it is my object to provide a case of this character in which a mirror is hingedly connected to the same hinge that connects the top and bottom members of the case, whereby when the case is opened out flat both the top and bottom members of the case may rest upon a stationary support and the mirror can be supported at any desirable angle for convenience of the operator on a firm base composed of the top and bottom members; and further in this connection it is my object to provide a mirror for a case of this character which is readily and easily accessible and easily cleaned.

A further object is to provide a case of this character in which the bottom and top case members may be closed and yieldingly held in a closed position, and yet may be readily and easily opened so as to expose either the top or bottom member as may be desired.

A further object is to provide improved means for retaining a powder cake in a case of this character, and for readily and easily removing the powder cake tray when the powder has been used up.

A further object is to provide an improved rouge cake and cosmetic container of simple and inexpensive construction, so arranged as to occupy a minimum of space within the vanity case.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of a case embodying my invention, with the top and bottom members open and the mirror

standing in an elevated position between them.

Figure 2 shows an enlarged, vertical, central, sectional view on the line 2—2 of Figure 1.

Figure 3 shows a face of the mirror and its rim.

Figure 4 shows a sectional view on the line 4—4 of Figure 3 showing the mirror in modified form.

Figure 5 shows an enlarged, detail, sectional view on the line 5—5 of Figure 1, illustrating the cosmetic stick retainer, and showing a cosmetic stick in position therein.

Figure 6 shows an enlarged, detail, vertical, sectional view through the case when in a closed position, and illustrating the position of the top and bottom case members and mirror when closed, and also illustrating the projecting handle on the mirror member for use in opening the case.

Figure 7 shows a front elevation of the part illustrated in Figure 6; and

Figure 8 shows an enlarged, detail view illustrating a part of the powder receiving pan and the lugs thereon for holding the powder cake in position within the pan and for holding the pan in position within the case.

Referring to the accompanying drawings I shall first describe the bottom or powder retaining member of the case. It is formed complete of a single piece of sheet metal and comprises a bottom 10 and upright sides 11. Near the upper end of the sides there is formed an inwardly extending shoulder 12 and above the shoulder the sides extend vertically at 13.

The powder containing pan is also formed of a single piece of sheet metal and comprises a flat bottom member 14 and upright sides 15. At spaced intervals throughout the upright sides 15 I form a series of lugs 16. These are made by cutting the lugs out of the material of the sides 15. After the insertion of the powder cake 17 these lugs are bent inwardly to retain it in position. At other intervals throughout the circumference of the sides 15 I provide other lugs 18 formed in the same manner but inclined slightly outwardly.

When the powder pan is inserted in the case, these lugs 18 spring inwardly and then when the pan is below the shoulder 12, they spring outwardly and engage the shoulder,

thus securely holding the pan within the bottom case member, but obviously the pan may be readily, easily and quickly removed by simply bending the lugs 18 inwardly with a knife blade or the like until they stand clear of the shoulder 12.

To one side of the bottom case member I have affixed a hinge 19, and in the side diametrically opposite from the hinge I have 10 formed a notch 20 for purposes hereinafter made clear.

The top case member is formed of a single piece of sheet metal and comprises a flat top member 21 with vertical sides 22. In the 15 vertical sides 22 I have formed an inwardly extended rib 23, clearly shown in Figure 6, and below the rib 23 the part indicated by the numeral 24 stands straight downwardly in line with the part 22, and the diameter of 20 the part 24 is slightly greater than that of the corresponding part 13 of the bottom case member so that the top member 24 will telescopically receive the part 13, as shown in Figure 6.

25 This top member is designed to contain a rouge cake and cosmetic sticks, and for this purpose I have provided a partition comprising a substantially flat sheet metal body portion 25 having at its center a rectangular depression 26 and fitted in this depression is a rouge pan 27, also made of sheet metal and containing a rouge cake 28. This pan is detachably fitted in the depression formed in the partition member 25 and is yieldingly 30 held in place by friction, and can be readily removed with a knife blade or the like.

At the opposite sides of the rouge cake pan I have provided receptacles for two or 40 more cosmetic sticks. These receptacles are formed of the same material of which the partition member 25 is formed, and a part of this material is arched upwardly, as shown at 29 in Figure 5. Another part adjacent thereto is arched downwardly at 30, 45 and the part 30 is provided with a tongue 31, which tongue is formed by cutting it out of the material of which the part 29 is formed, thus leaving a slot at 32 in the part 29. This tongue 31 is curved slightly upwardly, as shown in Figure 5. A cosmetic stick 33 may be readily and easily inserted 50 in the depression 30 and then moved to position under the raised portion 29, during which movement it will engage the spring 55 tongue 31 and thereby be yieldingly held in position so that the point of the cosmetic stick is protected and sealed by the part 29.

By this construction these cosmetic sticks 60 occupy the same space vertically within the cover member as is occupied by the rouge cake. The cover member is connected to the hinge 19 at one side, and at its other side there is formed a notch 34 for purposes hereinafter made clear.

65 The mirror is preferably formed of a sin-

gle piece of sheet metal 35, nickle plated and highly polished to form a mirror on both sides. At one side, this mirror is hingedly connected to the hinge 19, and at its other side there is formed a handle 36.

In Figures 3 and 4 I have shown a modified form of the mirror which is composed of two relatively thin plates of glass 37 and 38, having their adjacent faces silvered in the well known manner in which mirrors are 75 customarily formed.

Surrounding these two mirror members and firmly connecting them together is a sheet metal channel shaped rim 39, having formed at one side a hinged member 40, and 80 at the other side a handle member 41.

In practical use it is obvious that the entire device is cheap and inexpensive in its construction, and may be made relatively thin in proportion to its diameter. The 85 powder pan is inexpensive in its construction, and after the powder has been placed in position, the retaining lugs 16 may be bent downwardly over the powder, thus firmly and securely holding the powder in position. The powder pan may be readily and easily forced with a gentle pressure into position within the bottom member 11, and when the lugs 18 pass the shoulder 12 they 90 will spring outwardly and firmly retain the 95 powder pan in position.

The rouge and cosmetic stick holder is of simple, and inexpensive construction and may be formed complete of a single piece of sheet metal, and can be forced into position 100 past the rounded lugs 23 so that it will be firmly and permanently held. The partition member 25 need not be removed because the rouge holder pan is detachably connected therewith.

The mirror, whether made of a single 105 piece of sheet metal or made of two thin pieces of glass with a metal rim, is connected permanently to the same hinge that the top and bottom case members are hinged to, and when closed the mirror is supported in position substantially flush with the top edge of the bottom member, as shown in Figure 6. When in this position, the handle member 36 projects outwardly through the 110 notches 20 and 34.

When it is desired to open the box, the operator may very readily and easily expose either the powder side or the rouge side. If it is desired to expose the rouge side, the 115 operator grasps the powder side of the case in one hand and the handle member 36 in the other and pulls the handle member upwardly, thus causing the handle member to throw open the rouge member and the 120 mirror. Or, if it is desired to expose the powder member, the operator grasps the rouge member in one hand and the handle 125 36 in the other and moves them apart, thus exposing the powder member and leaving the 130

mirror member in position over the powder member. When the case is open the mirror may be freely swung from one side to the other.

5 I claim as my invention:

1. A vanity case comprising top and bottom pan members the top pan member having its inner sides provided with an inwardly extending bead, the inner side of said bottom pan being provided with an inwardly extending shoulder, a mirror member slightly smaller than the said pan members, the said pan members and said mirror member being hingedly connected at a common 10 point, the open edges of said pans being provided with notches on opposite sides from their hinged portion, said pans being so constructed that the open edge of one will telescopically receive the open edge of the other when the pans are in a closed position, 15 a handle portion designed to extend outwardly through the notched portion of said pans when they are in a closed position, a partition member secured between the bead of 20 said top member and the closed end of the same, said partition member being provided with a centrally located rectangular depression, a rouge pan detachably secured in 25 said depression, the said partition being provided at each side of said depression with a receptacle for receiving a cosmetic stick, each of the said receptacles being provided with a flexible tongue for yieldably securing the stick in position, the said bottom pan 30 being provided with a detachable powder pan, the said powder pan having side members with outwardly extending lugs to engage the shoulder of said pan and other lugs designed to be bent inwardly for securing 35 a cake of powder in position within said pan.

2. A vanity case comprising top and bottom pan members, the top pan member

having its inner sides provided with an inwardly extending bead, the inner side of said bottom pan being provided with an inwardly 40 extending shoulder, a mirror member slightly smaller than the said pan members, the said pan members and said mirror member being hingedly connected at a common point, the open edges of said pans being 45 provided with notches on opposite sides from their hinged portion, said pans being so constructed that the open edge of one will telescopically receive the open edge of the other when the pans are in a closed position, 50 the said mirror member being provided with a handle portion designed to extend outwardly through the notched portion of said pans when they are in a closed position, a partition member secured between the bead 55 of said top member and the closed end of the same, said partition member being provided with a centrally located rectangular depression, a rouge pan detachably secured in 60 said depression, the said partition being provided at each side of said depression with a receptacle for receiving a cosmetic stick, each of the said receptacles being provided with a flexible tongue for yieldably securing the stick in position, the said bottom pan 65 being provided with a detachable powder pan, the said powder pan having side members with outwardly extending lugs to engage the shoulder of said pan and other lugs designed to be bent inwardly for securing 70 a cake of powder in position within said pan.

Des Moines, Iowa, October 7, 1922.

GUY G. MARTIN.
